UNITED STATES PATENT OFFICE

WILLIAM M. HUESEMAN, OF DILLSBORO, INDIANA

COMBINED BUCKLE AND BUTTON LOOP

Application filed January 3, 1930. Serial No. 418,366.

This invention relates to buckles, buttons and clasps and more particularly to a buckle of the type applied to shoulder straps of a pair of overalls and adapted to engage buttons upon the bib of the overalls.

One object of the invention is to so form the buckle that it may be very easily applied to a shoulder strap of a pair of overalls and held in an adjusted position thereon with the button-engaging portion of the buckle disposed in front of the strap and thereby allowing the lower end portion of the strap to extend behind the bib of a pair of overalls where it will be out of the way.

Another object of the invention is to provide the buckle with securing prongs so formed that the buckle may be held in an adjusted position upon the strap without the prongs penetrating the strap thereby preventing the strap from being weakened due to openings formed therein, eliminating danger of a person being cut or scratched by sharp prongs, and also permitting the buckle to be easily and quickly shifted from one place to another upon the strap.

Another object of the invention is to provide a buckle which may be stamped from sheet metal and thereby not only allow the buckle to be cheaply produced but also eliminate parts movable relative to each other and liable to come apart or move out of their proper positions.

Another object of the invention is to eliminate an extra slide required when a buckle having prongs is used. The extra slide referred to above is an added expense and also uncomfortable as it comes too far upon the shoulder and presses against the collar bone.

Another object of the invention is to so form the buckle that ample space is provided for passage of a button through the buckle and thereby allow the buckle to be very easily engaged with a button or detached from the same.

The invention is illustrated in the accompanying drawing, wherein

Figure 1 is a view in front elevation showing the buckle applied to a shoulder strap by a pair of overalls and engaged with a button upon the bib,

Fig. 2 is a view looking at the inner face of the shoulder strap with the buckle applied thereto,

Fig. 3 is a longitudinal sectional view through the strap and buckle taken on the line 3-3 of Fig. 2, and

Fig. 4 is a perspective view of the buckle.

This improved buckle, which is indicated in general by the numeral 1, is stamped from sheet metal of sufficient thickness to prevent it from bending easily and is formed with an upper bar 2, a lower bar 3 and end bars 4 extending between and connecting the ends of the upper and lower bars. Between the upper and lower bars extends an intermediate bar which is severed between its ends in order to form arms 5 extending inwardly from the end bars toward each other. These arms are bent transversely in spaced relation to their free ends in order to form prongs 6 and the portions of the arms between their attached outer ends and the prongs and constituting shanks for the prongs are twisted, as clearly shown in Figs. 2 and 4. Therefore, the prongs extend upwardly from their shanks and by referring to Fig. 3 it will be seen that the prongs are of such length that they project upwardly into overlying relation to the upper bar. It should also be noted that these prongs are spaced somewhat from the outer or front face of the upper bar and since the intermediate bar of the blank from which the arms 5 are formed is cut straight across in order to form these arms the ends of the prongs are blunt. The lower bar 3 is formed intermediate its length with a depending U-shaped portion 7 located beneath the space between the upwardly extending prongs 6 and this U-shaped portion constitutes an eye or seat for receiving a button. Since the eye or seat 7 is located directly beneath the space between the two prongs, a button may be very easily passed through the buckle and engaged in the eye.

When this improved buckle is in use, the free end of the shoulder strap 8 is passed upwardly and outwardly between the upper bar 2 and the prongs 6 and the buckle moved along the shoulder strap until it is in approximately the desired position upon the strap.

The strap is then extended forwardly and downwardly and passed rearwardly through the buckle between the arms 5 and the lower cross bar. Therefore, the buckle, with the exception of its arms 5 and prongs 6, will be disposed in front of the shoulder strap and when the button 9 sewed upon or otherwise secured to the bib 10 of a pair of overalls is engaged through the eye or seat 7, the lower end portion of the shoulder strap will be disposed back of the bib where it will be out of the way. If it is found that the buckle has not been properly located upon the shoulder strap, it is merely necessary to draw the free end of the strap upwardly and the buckle can then be easily shifted upwardly or downwardly upon the shoulder strap to a desired position and the free end of the strap then again drawn downwardly until the strap is engaged over and against the prongs, as shown in Fig. 3. Strain exerted downwardly upon the buckle when the button is engaged therewith causes a very tight binding engagement between the strap and the free ends of the prongs and prevents the buckle from slipping upon the strap but since the prongs are formed with blunt ends they do not penetrate the strap. Therefore, no holes are formed in the strap and the strap will not be weakened. It should also be noted that since the prongs do not penetrate the strap their free ends are covered and there will be no danger of a person being cut or scratched by the prongs.

Having thus described the invention, I claim:

1. A buckle comprising a plate cut to form upper and lower bars, end bars connecting the upper and lower bars, and a center bar extending between said end bars, the lower bar having a U-shaped portion intermediate its ends defining a button-engaging eye and the center bar being cut intermediate its ends to form arms extending towards each other from the end bars, said arms being twisted in spaced relation to their attached ends and bent upwardly between the twists and their free ends to form shanks and prongs extending upwardly therefrom, the upper end portions of said prongs overlying the upper bar and formed with blunt ends.

2. A buckle comprising a frame having upper and lower bars and end bars connecting the upper and lower bars, said lower bar being formed with a button-receiving seat, and arms extending towards each other from the end bars, said arms being twisted in spaced relation to their attached ends and bent upwardly between the twists and their free ends to form shanks and prongs extending upwardly therefrom, the upper end portions of said prongs overlying the upper bar and formed with blunt ends.

3. A buckle comprising a frame having upper and lower bars and end bars connecting

the upper and lower bars, said lower bar being formed with a button-receiving seat, and arms extending towards each other from said end bars and bent upwardly in spaced relation to their ends to form shanks and prongs extending upwardly therefrom, said prongs having their upper end portions overlying said upper bar in spaced relation thereto.

In testimony whereof I affix my signature.
